UNITED STATES PATENT OFFICE.

MAX R. LEHMAN, OF QUINCY, ILLINOIS, ASSIGNOR TO QUINCY PATTERN COMPANY,
OF QUINCY, ILLINOIS, A CORPORATION OF ILLINOIS.

COMBINATION COAL AND GAS RANGE.

1,231,391.

Specification of Letters Patent. Patented June 26, 1917.

Application filed October 11, 1916. Serial No. 125,023.

To all whom it may concern:

Be it known that I, MAX R. LEHMAN, a citizen of the United States, residing at Quincy, in the county of Adams and State 5 of Illinois, have invented certain new and useful Improvements in Combination Coal and Gas Ranges, of which the following is a specification, reference being had therein to the accompanying drawing.

10 This invention relates to certain new and useful improvements in combination coal and gas ranges, the object of the invention being to provide a range in which the oven thereof is provided with a continuous 15 burner chamber extending around three of its sides beneath the bottom thereof into which can be quickly inserted or removed therefrom a substantially U-shaped burner, the legs of which extend into the burner 20 chambers formed on the sides of the oven in such a manner that the hot air and products of combustion rising from the burner will be distributed equally within the oven.

Another object of my invention is to provide a construction of range in which the 25 usual form of oven which is surrounded by the ordinary coal flues is not changed to any extent, the bottom flue of the range being formed with burner chambers to receive the 30 burner, said burner chambers communicating with the lower portion of the oven through the medium of gratings.

Another object of my invention is to provide a combination coal and gas range with 35 an oven having a vent in the top thereof for the escape of the hot air and products of combustion which is protected by a baffle so as to prevent the products of combustion rising from the fire-box when the stove is 40 being used as a coal stove from passing into the oven.

Another object of the invention is to provide the burner chambers with air inlets so as to obtain the proper combustion and to 45 supply air freely to the burners so that the hot air and products of combustion will be conveyed through the oven in order to enable the oven to bake quickly.

Other and further objects and advantages 50 of the invention will be hereinafter set forth and the novel features thereof defined by the appended claims.

In the drawings,

Figure 1 is a longitudinal vertical section

through the stove constructed in accordance 55 with my invention showing the side burner chambers and the oven vent;

Fig. 2 is a section taken on the line 2—2 of Fig. 1;

Fig. 3 is a horizontal section on the line 60 3—3 of Fig. 1;

Fig. 4 is a perspective view of my improved construction of burner;

Fig. 5 is a detail perspective view of a 65 portion of a casing of the stove showing the construction of a stove at the right hand corner in order to enable the burner to be inserted within the burner chambers; and

Fig. 6 is a section taken on the line 6—6 70 of Fig. 3.

In carrying out my invention I employ a stove having the usual fire-box 1, ash-pit 2 and oven chamber 3 which is surrounded by the ordinary coal flues in order to enable the products of combustion from the fire-box to circulate around the oven in the ordinary manner as stoves of this character now in use. The top of the stove is preferably provided with a foraminated portion 4 under which are adapted to be placed burners not shown. The oven chamber 3 has vent openings 5 formed in the top thereof for allowing the products of combustion entering the oven from the burning chamber to circulate through and around the same 85 when the dampers have been adjusted, the construction of dampers forming no part of this invention.

Arranged over the outlet vents 5 of the oven is a baffle 6 for preventing the products 90 of combustion rising from the fire-box 2 from entering the oven when the stove is being used as a coal stove, and for deflecting the escaping products of combustion and hot air toward the side flues.

Arranged beneath the oven chamber 3 are side burner chambers 7 and 8 which communicate with a front burner chamber 9 in order to form a continuous substantially U-shaped burner chamber extending around 100 the two sides and front of the oven as clearly shown in Fig. 3.

The side burner chamber 7 is formed by a housing and communicates with the oven chamber through a grating 10 which can 105 be readily removed, the bottom of the chamber being provided with air inlets 11 and the end of the chamber is provided with air

inlets 12 at the back of the stove in order to supply air freely to the burners which will be hereinafter fully described.

6 The side burner chamber 8 is formed by cutting away the lower corner of the oven and securing thereto a substantially U-shaped housing, said housing communicating with the oven chamber through a removable grating 13. The chamber 8 extends to 10 the rear of the stove and is provided with air inlets 8'.

15 A front burner chamber 9 is formed by cutting off a portion of the bottom flue by arranging a longitudinally disposed obliquely arranged plate therein, and the top 20 of the burner chamber 9 is closed by a grating 14 and the chamber is provided with air inlets 15 beneath the oven door.

25 The lower corner of the side flue of the stove at the front of the same is cut away and a casing 16 is inserted in the cut-away portions forming a passageway which communicates with the end of the front burner chamber 9 and is of such a size that the mixing bell 17 of my improved construction of burner 18 can be readily forced through the same when the gratings are removed and the oven door is in open position. My improved construction of burner 30 18 is substantially U-shaped as shown having branches 19 and 20 adapted to extend into the side burner chambers 7 and 8, the burner being preferably formed of piping having perforations or cuts.

35 From the foregoing description it will be seen that I have provided a stove in which the oven has burner chambers communicating with the lower portion thereof along two of its sides and the front thereof, which 40 chambers are closed by removable gratings which when removed form a substantially U-shaped burner chamber into which extends an opening from the outside of the stove to receive the intake of the burner, said intake 45 having a mixing bell to receive a valve controlled gas supply pipe.

In order to insert my improved construction of burner into a stove as herein shown and described, the gratings covering the 50 burner chambers are removed and the burner 18 is placed into the oven and canted so that the bell 17 can be forced outwardly through the opening 16 and the body portion and branches 19 and 20 of the burner can then 55 be dropped into position within the side and front burner chambers, and by covering the chambers with the gratings the burners will be protected.

When the burner is in position within the 60 burner chambers of the stove, air is supplied freely to the burner chambers through the air inlets 11, 12, 15 and 8' which causes a circulation of the hot air and products of combustion through the oven to pass out of 65 the vents 5 into the flues of the stove and

around the oven so as to thoroughly heat the same.

I claim:

1. A combined solid fuel and gas burning stove having an oven therein, provided with the usual flues, said oven having vents communicating with the top flue thereof, burner chambers arranged below said oven and communicating therewith along two of its sides and front thereof, and a burner arranged 75 within the front burner chamber having branches extending into side burner chambers, said burner chambers having air inlets.

2. A combination solid fuel and gas burning stove having an oven therein provided 80 with the usual flues, said oven having vents in the top communicating with the top flue of the stove, burner chambers arranged below said oven and communicating with said oven along its sides and front, the front 85 chamber having an opening communicating therewith extending through the side flue of the stove, a substantially U-shaped burner removably mounted within said burner chambers and having a portion extending 90 out through the opening thereof, said burner chambers having air inlets and gratings arranged within said oven for closing said burner chambers.

3. A stove having an oven provided with 95 vents in the top thereof, said oven being cut away along two of its side edges and the front thereof, gratings arranged over said cut away portions, burner chambers arranged under said cut away portions forming 100 a substantially continuous chamber around the side edges and front of said oven, and a substantially U-shaped burner arranged in said burner chambers.

4. A stove having an oven provided with 105 vents in the top thereof, said oven having its lower corners cut away at the side edges thereof and the bottom adjacent the front edge thereof, gratings arranged over said cut away portions, burner chambers arranged under said cut away portions forming 110 a continuous substantially U-shaped chamber extending around two of the side edges and the front of said oven, said burner chambers having air inlets, the front burner 115 chamber having one of its ends arranged in alignment with an opening formed in the wall of said stove, and a substantially U-shaped burner arranged in said burner chambers having a mixing bell extending 120 through said opening.

5. A combined solid fuel and gas burning stove having an oven therein surrounded by the usual flues, said oven having vents communicating with the top flue of said stove, 125 a deflecting baffle arranged over said vents, a substantially U-shaped burner chamber formed beneath said oven, and communicating therewith along two of its side edges and the front thereof, said burner chambers hav- 130

ing air inlets and a substantially U-shaped burner detachably mounted in said U-shaped burner chamber.

6. A combined solid fuel and gas burning stove having an oven therein surrounded by the usual flues, said oven being cut away along its lower side edges, burner chambers arranged under said cut away portions having air inlets at their rear ends, said oven having a cut away portion in its bottom along the door opening thereof, a burner chamber arranged beneath said cut away portion having air inlets and communicating at one end with an opening formed in the wall of said stove, a substantially U-shaped burner arranged within said burner chamber having a mixing bell extending through the opening of the wall of said stove, and gratings arranged over the cut away portions of said oven for closing said burner chambers.

7. A combined solid fuel and gas burning stove having an oven therein surrounded by the usual flues, said oven having its lower corners cut away, burner chambers arranged under said cut-away portions, said oven having its bottom along the door opening cut away, a burner chamber arranged under said cut away portion having air inlets, said side burner chambers having air inlets at their rear ends, said front chamber communicating at one end with a casing extending through the side flue of said stove, a substantially U-shaped burner arranged within the front burner chamber having its branches thereof disposed in the side burner chambers, said burner having a mixing bell extending through said casing, and gratings removably mounted over said burner chambers.

8. A combined solid fuel and gas burning

stove having an oven therein surrounded by the usual flues, said oven having vents communicating with the top flue of said stove, a substantially U-shaped burner chamber formed beneath said oven and communicating therewith along two of its side edges in the front thereof, said burner chamber being provided with air inlets, a casing extending through the side flue of said stove communicating with said burner chamber at one corner thereof, a substantially U-shaped burner arranged within said burner chamber having a mixing bell extending through said casing, and removable gratings arranged within said oven over said burner chamber.

9. A combined solid fuel and gas burning stove having an oven therein surrounded by the usual flues, said stove having a substantially U-shaped burner chamber arranged beneath the oven and communicating therewith, and a detachable substantially U-shaped burner arranged within said burner chamber.

10. A combined solid fuel and gas burning stove having an oven therein surrounded by the usual flues, said stove having a substantially U-shaped burner chamber arranged beneath the oven and communicating directly therewith at the lower corners thereof, a detachably substantially U-shaped burner arranged within said burner chamber and removable gratings arranged over said burner chamber.

In testimony whereof I hereunto affix my signature in the presence of two witnesses.

MAX R. LEHMAN.
